TIME INDICATOR FOR CLOCKS AND
WATCHES

William T. Jefferson, Los Angeles, Calif.

Application October 31, 1941, Serial No. 417,241

4 Claims. (Cl. 58—57)

This invention relates to an improvement in time indicator for clocks and watches and consists of the matters hereinafter described and more particularly pointed out in the appended claims.

The object of my invention is to provide a simple device to be mounted in operative relation with the dial of a watch or clock and provided with means, coacting with the dial, for indicating the time at which some act should be performed, the time of a radio program or an engagement, etc.

A great advantage of my invention lies in the fact that it can be attached in operative relation with the dial of any ordinary clock or watch without injury thereto.

I attain this object by the devices illustrated in the accompanying drawing, in which

Figure 1 is a front view of a clock having mounted thereon a device embodying my invention.

Figure 2 is a fragmentary view on an enlarged scale showing a section through Figure 1 in a plane indicated by the line 2—2 of Figure 1.

Figure 3 is a front perspective view of a device embodying my invention.

Figure 4 is a rear perspective view of a device embodying my invention.

Figure 5 is a view in elevation of an indicator used in my invention.

Figure 6 is a view in elevation of a modified form of indicator used in my invention.

Referring now to the embodiment of my invention illustrated in the drawing: The device includes a body of penetrable material 10, preferably of felt, cut circular or in any desired shape and of suitable size, and provided with means on one side for attaching it to the outer surface of the crystal of a watch or glass covering of a clock dial, an ordinary adhesive that may be softened by moisture being suitable for the purpose. The body 10 is of some material such as felt that is easily penetrable by a pointed indicator 18, but of sufficient rigidity to hold the indicator securely in position when its pointed end is inserted therein. The indicator 18 as shown in Figure 5 consists of a thin shaft 16 pointed at one end and having a bulb or disc 14 at the other end, the latter being sufficiently large and of a color to be distinctly noticeable against the background of the dial while the thinness of the shaft 16 will prevent the indicator from being confused with the hands of the clock, or the same purpose may be accomplished by giving the entire indicator a color 55

strongly contrasting with the color of the clock hands.

The body 10 may be provided on its outer face with minute and hour markings corresponding in angular position with the numerals and graduations on the clock dial, but this is not absolutely essential as the pointed indicator 18 when inserted radially in the edge of the body 10, as shown at 14^a in Figure 1 will cooperate with the numerals and graduations on the dial of the clock. As indicated at 17 in Figure 5 the outer end of the indicator may be provided with a pointed projection to insure exactness in placing the indicator in registry with the desired point on the clock dial. If desired, however, the outer face of the body 10 may be provided with hour and minute numerals and graduations, as illustrated, to assist in placing the indicator in the desired position. Instead of inserting the indicator radially of the body 10 and parallel to the clock dial it may be inserted in an inclined position or perpendicular to the dial as shown at 14^b in Figures 1 and 2, although the radial position will generally be found preferable. A plurality of pointed indicators may be provided each having a characteristic shape or marking to designate some particular event or purpose connected with the time at which the indicator is set. As illustrative of such purpose I have in Figure 6 of the drawing shown an indicator with a disc at the outer end bearing the letters KFD indicative of the call letters of a broadcasting station.

The use and operation of the device is as follows: Assume that a person wishes to hear programs of a radio station to be presented at, say, 3 o'clock and 8 o'clock. Indicators are inserted at points in the body 10 corresponding to the hours 3 and 8 as shown in Figure 1, the indicator at the hour 3 being shown as inserted in a position perpendicular to the clock dial, and that at the hour 8 being inserted radially of the dial and body 10 and parallel to the dial so as to cooperate with the numerals and graduations on the clock dial. Afterwards, when the small or hour hand of the clock reaches and coincides with the positions of the indicators, a person would know that it was the time of the desired programs. The device can also be used in a similar manner to indicate the time at which some act is to be performed or an engagement kept.

I claim as my invention:

1. The combination of a clock provided with a dial and indicating hands and a transparent cover thereon, of a penetrable body, means for

attaching said penetrable body to said cover centrally of said dial, the outer face of said body being provided with a circular series of time numerals and graduations corresponding in angular position with those on the clock dial, and a pointed indicator adapted to be inserted and held in said body at a position to indicate any desired time.

2. The combination with a clock provided with a dial and indicating hands and a transparent cover thereon, of a penetrable body, means for attaching said penetrable body to said cover centrally of said dial, and a pointed indicator adapted to be inserted and held in said body in cooperative relation with the time numerals and graduations on the clock dial.

3. The combination of a clock provided with

a dial and indicating hands and a transparent cover thereon, of a penetrable body, an adhesive on one face of said body, the other face being provided with a circular series of time numerals and graduations corresponding in angular position with those on the clock dial, and a pointed indicator adapted to be inserted and held in said body at a position to indicate any desired time.

10 4. The combination with a clock provided with a dial and indicating hands and a transparent cover thereon, of a penetrable body, an adhesive on one face of said body, and a pointed indicator adapted to be inserted and held in said body in cooperative relation with the time numerals and graduations on the clock dial.

WILLIAM T. JEFFERSON.
